UNITED STATES PATENT OFFICE.

JULIUS KELLER, OF FOND DU LAC, WISCONSIN.

DETONATOR.

1,221,454.

Specification of Letters Patent.

Patented Apr. 3, 1917.

Application filed July 29, 1916. Serial No. 111,971.

To all whom it may concern:

Be it known that I, JULIUS KELLER, a citizen of the United States, residing at Fond du Lac, in the county of Fond du Lac and State of Wisconsin, have invented certain new and useful Improvements in Detonators, of which the following is a specification.

The object of this invention is to improve the construction of detonators used in explosive shells.

In the accompanying drawings, Figure 1 is a longitudinal central sectional view of a detonator embodying the features of my invention. Fig. 2 is an enlarged view of the forward end of a slidable rod comprised in the detonator, showing a detent attached thereto. Fig. 3 is a section on line 3—3 of Fig. 2. Fig. 4 is a perspective view of the detent.

The detonator comprises a casing 1 adapted to be secured within the body or casing of a shell. Stationarily mounted within the casing 1 is a ring 2 to which is fixed a firing needle 3. Said needle is located in the axis of a tubular rod 4 which is slidable longitudinally of the casing 1. To the inner end of the rod 4 is fixed a detonator cap 5. Surrounding the needle 3 and the rod 4 is an annular chamber 6 containing the bursting charge. When the rod 4 slides forward in the casing 1, the cap 5 is carried against the point of the needle 3, thereby detonating the bursting charge.

Normally the rod 4 is held against sliding movement by means of a compression spring 7, and by means of a detent 8. Said detent comprises a base 9 lying against the forward

end of the rod 4, and two fingers 10 lying in contact with opposite sides of the rod. The end portions of the fingers 10 are bent to provide yieldable projections 11 which lie in contact with portions 12 that are stationary with relation to the casing 1.

The detent 8 is secured to and centered upon the rod 4 by forcing portions 13 of the arms 10 into recesses, countersinks or depressions 14 in the rod. This may be done by pressing any suitable centers or dies (not shown) against the arms 10 to force the metal of said arms into said recesses, thus producing the bosses 13. It will be seen that the means herein disclosed for securing the detent to the rod and for centering the detent thereon is very simple and inexpensive.

Upon concussion, the rod 4 is driven forward in the casing 1 through momentum, the projections 11 yielding or flattening out to allow the rod to slide.

I claim as my invention:

A detonator comprising a casing, a rod slidable axially of the casing, a detent for normally preventing movement of the rod, said detent comprising a base lying against the end of the rod and two arms lying at the sides of the rod, said arms being bent to provide yieldable locking projections, stationary portions in the casing against which said projections lie, and bosses integral with the arms and lying in depressions in the rod for centering and securing the detent to the rod.

In testimony whereof, I have hereunto set my hand.

JULIUS KELLER.
